Primary Examiner — Christian P. Mclean

CLAIM

The ornamental design for a dowel connector, as shown and described.

DESCRIPTION

FIG. 1.1 is a perspective view of the dowel connector

FIG. 1.2 is a front view thereof;

FIG. 1.3 is a right side view thereof; and

FIG. 1.4 is a left perspective view thereof.

The portions of the dowel connector shown in broken lines form no part of the claimed design.
